UNITED STATES PATENT OFFICE

2,617,513

RIBBON REVERSING MECHANISM

Ralph E. Zum Bahnen, Homewood, and Leland H. Snyder, Lincolnwood, Ill., assignors to Stenographic Machines, Inc., Chicago, Ill., a corporation of Illinois

Application December 30, 1949, Serial No. 135,902

2 Claims. (Cl. 197—165)

1

The present invention relates to a shorthand machine of the character that is provided with a plurality of type bars equipped with type that operate against a rotatable platen. A sheet of paper is mounted to pass over the platen and an inked ribbon is disposed between the type and the paper so that as the type strikes the platen, the inked impression of the type is deposited onto the paper.

The ribbon is mounted on a spool and is progressively fed from this first spool across the path of the type onto a second spool. Each time a typed impression is made a fresh portion of the inked ribbon is fed into the path of the type so that no part of the ribbon is used twice in succession by the same type.

After most of the ribbon has been fed from the first spool onto the second spool as the result of a succession of strokes of the type bars, the direction of feed of the ribbon is reversed so as to return the ribbon from the second spool onto the first spool. Once again this return movement is progressive in response to the strokes of the type bars.

The present invention has to do primarily with this ribbon feeding and reversing mechanism. It is important that the feed be uniform and that reversal of the direction of feed be effected at the right moment and without interruption to the strokes of the type bars.

These type bars are operated by a plurality of key levers, each of which is provided at one of its ends with a key. These keys are all arranged so as to form a keyboard. In machines of the shorthand variety it is very important that the "touch" of the keys be soft. In other words, the effort required to depress the keys should be very slight. It is equally important that at all times this touch be uniformly soft. Since the movement of the inked ribbon responds to the depressions of the keys, the mechanism bringing about this movement must be smooth in its operation, offering only a minimum amount of resistance. The reversal of feed of the ribbon must likewise be effected without increasing the amount of force or exertion needed to depress the keys for otherwise the "touch" of the keys would change every time a reversal in the direction of feed of the ribbon is accomplished.

Shorthand machines of the class described herein are ideal for taking rapid dictation or for reporting rapid conversations or testimony. They are used very effectively for court and conversation reporting where speed as well as accuracy is of paramount importance. It is, therefore, essen-

2

tial that the machine function perfectly at all times without interfering with or distracting the operator. Nothing can be more annoying to the operator than to have the ribbon feed fail or lock. Such failures are eliminated by the present invention because the operation of the ribbon mechanism is positive and completely reliable.

All of the foregoing constitute some of the principal objects and advantages of the present invention, others of which will become apparent from the following description and from the drawings, in which

Fig. 1 is a plan view with a portion broken away, of a shorthand machine embodying the present invention;

Fig. 2 is a fragmentary, longitudinal, sectional view taken through the machine, a portion of the machine mechanism being illustrated in elevation, and showing in particular the drive for the ribbon mechanism;

Fig. 3 is a longitudinal sectional view taken through the machine with portions of the machine mechanism illustrated in elevation and illustrating the clutch drive mechanism for the machine platen;

Fig. 4 is a detail side elevational view of the drive mechanism for the ribbon and the clutch drive mechanism for the machine platen;

Fig. 5 is an enlarged top plan view of the ribbon drive and reversing mechanism with the ribbon spools mounted in place and showing the reversing mechanism in position for driving the right hand spool;

Fig. 6 is a vertical sectional view through the ribbon drive and reversing mechanism, the view being taken on the line 6—6 of Fig. 5;

Fig. 7 is an enlarged, fragmentary plan view of the drive shaft and clutch mechanism for operating the ribbon;

Fig. 8 is a transverse sectional view taken through the shaft along the line 8—8 of Fig. 7;

Fig. 9 is a view corresponding to Fig. 5 with the ribbon spools removed and showing the reversing mechanism in position for driving the left hand spool;

Fig. 10 is a vertical sectional view through the ribbon drive and reversing mechanism, the view being taken along the line 10—10 of Fig. 9; and

Fig. 11 is a fragmentary perspective view of the ribbon that is operated by the mechanism illustrated in Figs. 5 to 10 inclusive showing in particular the lug that actuates the reversing mechanism.

For purposes of illustration a single embodiment of the present invention has been selected for description, though it is recognized that nu-

merous modifications may be made in this specific embodiment without departing from the intended scope of the invention.

Referring first to Figs. 1 to 3 inclusive of the drawings, the present invention is illustrated in connection with a shorthand machine generally indicated at 15 that is used for recording dictation, conversation or the like, phonetically. The machine very generally comprises a frame that includes spaced side frame members 16. Mounted between these side frame members and supported thereby is a type bar assembly generally indicated at 17 and a platen 18, the latter of which is rotatably mounted between the side frame members 16. The type bar assembly 17 includes a plurality of type bars 17a that are adapted to move back and forth in a direction at right angles to the axis of the platen 18 and each type bar is provided with a head portion 19 on which is mounted the type letters or numerals. These type bars 17a are mounted in a conventional manner and are caused to move back and forth by a plurality of key levers 20, on one end of each of which is a key 21. These keys 21 are arranged to form a keyboard and upon depressing one of these keys 21, the corresponding type bar 17a is caused to move so that the head 19 engages the platen 18. The structure and mechanism connecting the keys to the type bars 17a form no part of the present invention and since this is now very conventional and well-known, a more complete description herein is believed unnecessary.

Mounted on the shaft of the platen 18 is a clutch 22 which may also be of any well-known variety that causes the platen 18 to rotate during the time any of the keys 21 are moving in a downward direction under the force of the operator's finger but allows the platen to remain stationary during the period that the key 21 is moving upwardly on the return stroke.

Once again the specific structure and operation of the clutch 22 is immaterial to the present invention and consequently a more detailed description herein is believed unnecessary. It will be sufficient for present purposes to explain merely that each of the key levers 20 as best shown in Fig. 4 operates against a pair of actuating arms 23 that is pivotally mounted on a shaft 24 fixed between the side frame members 16 in the machine. A pad 25 is mounted on one end of each of the actuating arms 23 and all of the key levers 20 rest on this pad as can be best seen in Figs. 1 and 2. Thus as the keys 21 are depressed each actuating arm 23 is caused to rock about the shaft 24. Mounted on the opposite end of each actuating arm 23 is an actuating abutment 26, one of which operates a clutch actuating mechanism generally indicated at 27 in Fig. 4 that is connected to the clutch 22. This clutch actuating mechanism 27 comprises a pair of links 28 and 29, the former of which is pivoted at one end at 30 and at the other end at 31 to one end of the link 29. The other end of the link 29 is pivotally connected at 32 to one element of the clutch 22. Adjustably mounted on the link 28 as at 33 is a disc member 34 that is adapted to be engaged by the actuating abutment 26. A spring 35 normally urges the clutch mechanism 27 in a downward direction to its normal position illustrated in Fig. 3. When a key 21 is depressed this clutch mechanism 27 is forced upwardly to the position shown in Fig. 4 by virtue of the operation of the actuating arm 23 so as to rotate the clutch 22 and hence

the platen 18. When the pressure on the key 21 is removed the mechanism returns to the position shown in Fig. 3 causing the clutch 22 to rotate in a counterclockwise direction, but during this return movement the platen 18 remains stationary as previously described.

The present invention has to do primarily with the ribbon mechanism which is generally indicated at 36 in Fig. 1. This ribbon mechanism 10 36 comprises a supporting base 37 which is best shown in Figs. 1 and 5 to 10 inclusive that is fastened to the machine side frame members 16 by means of screws 38 or some other suitable attaching means. This base 37 includes a flat 15 platform portion 39 and as shown in Fig. 10 foot-like portions 40 that are disposed at the opposite ends of the platform. As indicated in Figs. 5 and 9 the platform 39 is longitudinally slotted at 41 and disposed in this slot throughout 20 the length of the platform 39 is a shaft 42 that extends through the foot-like portions 40. One end of the shaft projects beyond the adjacent foot-like portions 40 so as to accommodate thereon a drive wheel 43. A washer 44 is mounted on 25 the other end of the shaft and a screw 45 is threaded into the end of the shaft to fix this end of the shaft to the supporting base 37. Similarly, a washer 46 is mounted against the other end of the shaft on the outside of the drive wheel 43 and a screw 47 threaded into the end of the shaft, fixes the drive wheel 43 in place on the shaft. This drive wheel 43 is keyed to the shaft 30 so that when the wheel rotates, like motion is imparted to the shaft.

Again referring to Figs. 2 and 4 it will be noted that one of the actuating arms 23 is also provided with a ribbon driving arm 48 that is fixed to rock with the actuating arm 23. Pivotally mounted on the free ends of the arm 48 is a pawl 49 that 35 is adapted to engage the periphery of the drive wheel 43. A spring 50 normally holds this pawl 49 against the periphery of the drive wheel 43. This drive wheel 43 may be made out of rubber, fabric or some other suitable material that provides traction between the surface of the wheel 45 and the pawl 49. The engaging surface of the pawl 49 is also serrated as shown at 49a to increase this traction. As the actuating arm 23 is rocked back and forth in a manner previously described, this motion is transmitted through the arm 48 and the pawl 49 to rotate the drive wheel 50 43. When viewed in Fig. 4 the downward movement of the key 21 moves the pawl 49 in a downward direction so as to rotate the drive wheel 43 in a counterclockwise direction. During the return stroke of the key 21 to its normal position 55 illustrated in Fig. 3, the pawl 49 merely slides over the surface of the drive wheel 43, but the wheel itself remains stationary during this return movement of the pawl. Referring to Fig. 2 a holding pawl 92 is pivotally mounted at 93. A drive wheel 56 engaging portion 94 serrated at 95 is provided on the free end of the pawl 92 and is adapted to engage the periphery of the drive wheel 43 in a clockwise direction as viewed in Fig. 2 to maintain pressure contact between the wheel engaging portion 94 and the periphery of the drive wheel. This holding pawl 92 prevents rotation of the drive wheel 43 during the return stroke of the first mentioned pawl 49 but allows the drive wheel 43 to be rotated during the downward stroke of keys 21. Since the drive wheel 43 is keyed or otherwise fixed to the shaft 42, rotation of the drive wheel 43 causes rotation of the shaft.

70 Referring now to Fig. 10 two gears 51 and 52

5

are loosely mounted on the shaft 42 at opposite ends thereof. Each of these gears 51 and 52 as best shown in Fig. 7 is provided with an inwardly extending clutch element 53 that comprises essentially a collar member having a plurality of tooth-like slots 54 spaced about the peripheral edge of the collar.

Again referring to Fig. 10 there is also mounted on the shaft 42 a sleeve 55 that is elongated but is somewhat shorter in length than the distance between the clutch elements 53 spaced at the opposite ends of the shaft. This sleeve 55 is keyed as at 56 to the shaft 42 so that any rotating motion imparted on the shaft 42 is transmitted to the sleeve 55. Each end of the sleeve 55 is provided with a clutch element 57 that has a pair of outwardly projecting clutch teeth 58 adapted to enter the tooth-like slots 54 in the adjacent clutch element 53. The sleeve 55 is adapted to slide longitudinally along the shaft 42 to permit one or the other of the clutch elements 57 to couple with the adjacent clutch element 53. As shown in Fig. 10 the clutch element 57 on the right hand side of the sleeve 55 is coupled with the adjacent clutch element 53 that is disposed on the right hand end of the shaft 42. If the sleeve 55 were shifted to the other end of the shaft 42 as shown in Fig. 5, then the clutch element 57 at the left hand end of the sleeve 55 is coupled with clutch element 53. Since the clutch element 53 is loosely mounted on the shaft 42 it can be rotated by shaft 42 only when the sleeve 55 is disposed in position to couple the corresponding clutch element 57 with the adjacent clutch element 53.

Secured to the top of the platform member 39 is a pair of spaced upstanding posts 59 and 60, both of which are mounted with their vertical center line disposed directly over the longitudinal center line of the slot 41 in the platform 39. Each of these posts 59 and 60 is provided with a base flange 61 and is firmly secured to the platform member in some suitable manner. Mounted on the post 59 is a spool driven gear 62 that is held on the post by means of a split lock ring 63 that fits in a groove in the wall of the post 59. Similarly, a spool driven gear 64 is concentrically mounted on post 60 and is locked in place by a split ring 65. Each of the gears 62 and 64 is adapted to rotate about its respective post 59 and 60.

As best shown in Fig. 9 peripheral gear teeth 66 are provided on the gears 62 and 64. These teeth 66 on gear 62 mesh with the teeth on the gear 52 that is disposed on the right hand end (as viewed in Figs. 9 and 10) of shaft 42, whereas the teeth on the gear 64 mesh with the gear 51 that is disposed on the left hand end of the shaft 42. Thus any rotating motion of either of the gears 51 or 52 impart rotating motion to the corresponding gears 64 or 62 about its respective post 59 or 60. A ribbon spool 67a is adapted to be mounted on post 59 and similarly a ribbon spool 67b is adapted to be mounted on post 60. Each of these spools is held in place on its respective post by a threaded hold-down screw 68.

Again referring to Fig. 9 each of the gears 62 and 64 is provided with a plurality of apertures 69 spaced about the gear and as shown in Fig. 10 each of the ribbon spools 67a and 67b is provided with a downwardly projecting lug 70 that enters one of these apertures 69 in the corresponding gear 62 or 64. Thus as either of the gears 62 or 64 is rotated similar rotating movement is imparted to the corresponding spool 67a

6

or 67b by virtue of the interlock between the lug 70 and one of the apertures 69 in the gear.

As best shown in Figs. 5 and 9, a reversing arm 71 is mounted on the platform 39 and is pivoted with respect to the platform about a screw 72. This arm 71 fits beneath the gears 62 and 64. The arm 71 extends substantially throughout the length of the platform 39 and is provided at each of its outer ends with upturned flanges 73 and 74 spaced apart to provide therebetween at 75 a ribbon aperture that will be explained hereinafter. A centrally disposed arm 76 is provided on the reversing arm 71 and extends transversely with respect to the platform 39 between the two gears 62 and 64. The end of this last mentioned arm 76 is provided with a lug 77 that has a more or less spherical shaped head.

Also pivotally mounted on the platform 39 by means of a screw 78 is a sleeve actuating arm 79 that is provided at its outer end with an upstanding shoulder 80. An inwardly projecting post or lug 81 is provided on the upstanding shoulder 80 and forms a seat for a compression spring 82 that is disposed between the upstanding shoulder 80 and the lug 77 on the arm 76. A socket member 83 is provided on the inner end of spring 82 and this socket member has a spherical-like seat 84 that receives the lug 77 on the arm 76. The other end of the sleeve actuating arm 79 is provided with a finger 85 that is held between a pair of spaced annular collar-like members 86 that are integral with the sleeve 55.

The reversing arm 71 is adapted to rock back and forth about the screw 72 between the position shown in Fig. 5 and the position shown in Fig. 9. The compression spring 82 holds the arm 71 in one or the other of these positions and as the arm 71 moves from one position to the other, this spring 82 is compressed between the end of the lug 77 and the shoulder 80 until the arm 76 reaches the dead-center position, at which time the reversing arm 71 is disposed with its long axis parallel to the shaft 42. As the arm 76 moves beyond dead-center the compression spring 82 forces the reversing arm 71 to the end of its travel.

As best shown in Fig. 9 the sleeve actuating arm 79 is contained in a depression in the wall of the platform 39, the walls of the depression being shown at 87. During the movement of arm 76 as just described the sleeve actuating arm 79 moves from the position shown in Fig. 9 where it rests against one of the walls 87 of the depression to the position shown in Fig. 5 where it engages the other wall of the depression. Thus the sleeve actuating arm 79 has limited motion and this motion is transmitted through the finger 85 to the sleeve 55 so as to slide the sleeve from one end of the shaft 42 shown in Fig. 9 to the other end of the shaft shown in Fig. 5. In this manner the movement of the sleeve uncouples the clutch element 53 disposed at the right hand end of the shaft as viewed in Fig. 9 and then couples the clutch element 53 that is disposed at the other end of the shaft. Thus the drive is shifted from gear 62 to gear 64.

Referring now to Fig. 1, one of the ribbon spools, which for purposes of illustration may be that shown at 67a, is provided with a supply of ribbon 90. This ribbon passes through the adjacent aperture 75 at the end of reversing arm 71, between the type portions of type bars 17a and the adjacent platen 18 and then between

the corresponding aperture 75 at the opposite end of the reversing arm 71 onto the ribbon spool 67b. During the operation of the machine the ribbon 90 is progressively fed from spool 67a onto spool 67b by virtue of the movement of keys 21, the movement of the keys being imparted to the spools in the manner previously described.

As best shown in Fig. 11 the ribbon 90 is provided adjacent to each of its opposite ends with an outwardly projecting lug 91 that is adapted to engage the walls of the adjacent aperture 75 to actuate the reversing arm 71. The position of each of these lugs 91 on the ribbon is such that as most of the ribbon is fed off of one spool 67a or 67b onto the other, the lug 91 engages the wall of the aperture to actuate the reversing arm 71 before all of the ribbon has been removed from the adjacent ribbon spool.

As shown in Fig. 1 the reversing arm 71 has just completed its reversing operation by virtue of the fact that the lug 91 disposed at the right hand side of the ribbon is in engagement with the walls of the aperture 75. As the machine is operated by depressing the keys 21 the ribbon 90 will commence to feed onto spool 67b from spool 67a. When it is time for a reversing operation to take effect the corresponding lug 91 that is disposed near the end of the ribbon portion contained on spool 67b (see Fig. 1) is brought into engagement with the walls of aperture 75 on the end of reversing arm 71 so that on continued movement of the ribbon 90 in a direction toward the platen 18, the reversing arm 71 is rotated in a clockwise direction as viewed in Fig. 1, to commence the reversing operation. As previously explained as soon as this clockwise movement of reversing arm 71 passes the dead-center position of arm 76, the compression spring 82 snaps the reversing arm 71 through the remaining clockwise movement of the other extreme position, at which time the spool 67a is brought into driving relationship with the shaft 42. Thus the reversing operation of the ribbon has been completed and the ribbon is now fed on the opposite ribbon spool.

Again referring to Fig. 9, an emergency sleeve actuating arm 97 is provided on the reversing arm 71 on each side of arm 76. If the sleeve actuating arm 79 should fail to shift the sleeve so as to disengage the gears at one end and engage the gears at the opposite end, the emergency sleeve actuating arm 97 is brought into contact with adjacent collar 86 to nudge the arm 79 past the dead-center position of the spring 82. The spring then causes the arm 79 to complete the reversing operation. This guarantees effecting the revers-

ing of the ribbon mechanism and makes for more dependability of the machine operation.

We claim:

1. A ribbon mechanism for a machine of the class described comprising a horizontal drive shaft, a pair of ribbon spools rotatably mounted about vertical axes disposed over the shaft, drive means operatively connected to drive each spool including separate clutch means, and selecting means for alternatively coupling one or the other of the clutch means into driving relationship with the drive shaft including a reversing arm adapted to pivot between two positions, a coupling member movable into engagement alternatively with the separate clutch means, spring means urging the coupling member selectively into engagement with one or the other of the clutch means, and actuating arm means on the reversing arm engaging the coupling member to actuate the coupling member independently of the spring means.

2. The combination of a platform, a horizontally disposed shaft rotatably mounted on the platform, a pair of ribbon spools rotatably mounted on the platform about vertical axes disposed above the shaft, a driven gear fixed to rotate with each spool, a driving pinion loosely mounted on the shaft adjacent to each driven gear and meshing with the corresponding gear, clutch means for alternatively placing the driving pinions in driving relationship with the shaft including a shiftable sleeve mounted on the shaft and keyed thereto, a reversing arm pivotally mounted on the platform, a toggle member pivotally mounted on the platform and adapted to pivot between two positions from one side of dead center to the other side of dead center, the toggle member being connected to the shiftable sleeve, spring means connecting the toggle member to the reversing arm and urging the toggle member into either of its positions past dead center, and sleeve engaging means on the reversing arm adapted to shift the sleeve in the event of failure of the toggle member.
